UNITED STATES PATENT OFFICE.

SEIGFRIED L. HOCKERT, OF CINCINNATI, OHIO.

DEVICE FOR ACTUATING MORTAR-PESTLES.

SPECIFICATION forming part of Letters Patent No. 311,580, dated February 3, 1885.

Application filed March 17, 1884. (No model.)

To all whom it may concern:

Be it known that I, SEIGFRIED L. HOCKERT, a resident of Cincinnati, in the county of Hamilton and State of Ohio, have invented certain 5 new and useful Improvements in Devices for Actuating Mortar-Pestles, of which the following is a specification.

My invention relates to an improvement in devices for actuating the pestle of a mortar.

10 The object of my invention is to provide a device which will securely hold the mortar in position, in combination with attachments to the pestle which hold it firmly in position, and yet allow it to be rotated easily under the 15 spring-pressure, for the purpose of more rapidly and uniformly triturating or pulverizing the material under the pestle, all of which will be fully set forth in the description of the accompanying drawings, in which—

20 Figure 1 represents a central vertical section of my improvement in position for use. Fig. 2 represents a bottom plan view of the bed-plate on which the mortar is set. Fig. 3 is a plan view of one of the feet of the stand- 25 ards.

25 A represents the mortar-table. It is provided with adjustable lugs *a*, which are secured in slots *b*, pierced in the table, as shown radially, so that the mortar may be held firmly 30 in position by the lugs, which may be adjusted to suit different sizes of mortars.

35 B represent serrated or notched standards, which are preferably secured to the table by slotted feet *c* and set-screws *D*, which pass through slots *d*, pierced in the feet of the standards *B*, for the purpose of adjusting the standards, if desired.

40 *e* represents notches formed on the sides of the standards to receive the pressure-spring *E*. Several notches *e* are provided on the edge of the standards *B*, so as to allow the spring *E*, which is held in position in the notches to be adjusted up or down to increase or decrease the pressure upon the top of the

pestle *H*. The spring *E* is preferably made of 45 an endless elastic band. It may be attached to the top of the pestle *H* in any desired manner. The tension of the spring *E* holds the pestle down, and yet its elasticity allows it to be rotated readily. Additional pressure may 50 be imparted to the top of the pestle by lowering the ends of the spring-band *E*. When thus arranged, the pestle can be rapidly and easily rotated under pressure of the spring, and the triturations accomplished in very 55 much less time and with much less fatigue than with the ordinary pestle.

I do not desire to limit myself to the form or shape of the standards *B* and notches *e*, as they may be variously modified without af- 60 fecting the principal feature of my invention.

Having described my invention, what I claim as new, and desire to secure by Letters Patent, is—

1. In combination with a mortar and pestle, 65 standards *B* and elastic pressure-band *E*, secured to the standards *B* and pestle *H*, sub-stantially as specified.

2. In combination with a mortar and pestle, the standards *B*, adjustably secured to the 70 table *A* and adapted to receive the elastic pressure-band *E*, substantially as shown and described.

3. In combination with the mortar and pestle, the table *A*, provided with means, sub-stantially as shown and described, for holding 75 the mortar, and having adjustably secured thereto standards *B*, said standards being provided with notches *e*, and the elastic pressure-band *E*, attached to the pestle and 80 adjustably secured to the standards, substan-tially as specified.

In testimony whereof I have hereto set my hand.

SEIGFRIED L. HOCKERT.
